UNITED STATES PATENT OFFICE.

SELMA W. JEFFS, OF SANTA MONICA, CALIFORNIA.

SUPPORT FOR INFANTS' BATHTUBS.

1,390,444.

Specification of Letters Patent. Patented Sept. 13, 1921.

Application filed June 13, 1921. Serial No. 477,095.

To all whom it may concern:

Be it known that I, SELMA W. JEFFS, a citizen of the United States, residing at Santa Monica, in the county of Los Angeles and State of California, have invented certain new and useful Improvements in Supports for Infants' Bathtubs; and I do hereby declare the following to be a full, clear, and exact description of the invention, such 10 as will enable others skilled in the art to which is appertains to make and use the same.

This invention relates to supports for infants' bath tubs, and has for its object to 15 provide a device of this character which will be simple in construction, comparatively inexpensive to manufacture, and more efficient in use than those heretofore proposed.

With these and other objects in view, the 20 invention consists in the novel details of construction and combinations of parts more fully hereinafter disclosed and particularly pointed out in the claims.

Referring to the accompanying drawings 25 forming a part of this specification, in which like numerals designate like parts in all the views:

Figure 1 is a diagrammatic plan view of a portion of a standard bath tub with the 30 present invention in place therein;

Fig. 2 is a transverse sectional elevational view of the parts shown in Fig. 1, the infant's tub being shown in place within the holder;

Fig. 3 is an enlarged detail sectional elevational view of a portion of the support;

Fig. 4 is a fragmentary end elevational view of the parts shown in Fig. 3, as seen from the left of the said figure; and

Fig. 5 is a cross sectional view taken approximately on the line 5—5 of Fig. 3, looking in the direction of the arrows.

1 indicates a so called "standard" bath tub of any suitable construction provided 45 with the sides 2 and 3 and bottom 4. As is well known, such tubes are usually of a size to accommodate an adult person, and are not well adapted for the bathing of very small children and babies. For this purpose there is usually provided a smaller tub such as 5 illustrated in Fig. 2 but when such tubs are employed the water must be placed therein from some other receptacle or else the smaller tub 5 must be placed upon the 55 bottom 4 of the standard tub 1, which is rather inconvenient for the mother or nurse

who is performing the bathing operation. Furthermore, unless the smaller tub such as 5 is placed within the larger tub 1, quite an appreciable amount of water therefrom will 60 inevitably be splashed out.

In order to overcome the above difficulties, I propose to provide a suitable supporting means whereby an infant's bath tub such as 5 may be readily supported within the standard tub such as 1 in close proximity to the faucets of the said standard tub, whereby water may be readily introduced into the smaller tub, and I further propose to support the said smaller tub at such a height as 70 will be most convenient to the person performing the bathing operation.

To this end, I provide a pair of transversely extending supporting members 6 and 7, each of which is made up of two parts 8 and 9. These said members 8 and 9 are suitably joined to hinge members 10 and 11 respectively, which hinge members are pivotally connected together by means of the hinge pin 12, upon which there is threaded a 80 wing or other nut 13, adapted to control the friction between the said hinge members, all as will more fully appear below.

Also secured to the said hinge members 10 and 11 are the curved supporting bars 15 and 16 which may take any desired shape to accommodate an infant's tub such as 5, and which are here shown as forming a substantial oval shape figure when the parts are in their operative positions. The said members 15 and 16 are preferably made of solid or tubular metal and are adapted to form a support for the flange such as 17 of the smaller tub 5, as will be readily apparent.

The members 9 are likewise formed of 95 solid or tubular material and one of their ends, if solid, is drilled and threaded as at 20 to receive a screw 21 provided with a rigid thumb nut 22, and a check nut 23, see Fig. 3. The screw member 21 also carries a 100 washer member 24, one face of which, 25, is preferably rounded to co-act with the companion face 26 formed upon the contact member 27 which is adapted to bear against the side of the tub such as 3 to support the 105 device. The said member 27 may carry a rubber pad such as 28 and it is provided with an enlarged opening 29 through which passes the screw 21. A nut 30 engages the threads of the said screw member 21 and 110 holds the parts in their assembled positions, while at the same time permitting of a rela-

tive movement between the contact member 27 and the screw 21 and washer 24, providing in effect a ball and socket joint.

- The provision of such a connection between the contact member 27 and the support such as 9 permits the device to be used with all sorts of tubs, both those which have straight sides as well as those which have inclined sides, as will be readily apparent.
- 10 As will also be apparent, the provision of the screw member 21 threaded into the member 9 as shown, together with its lock nut 23, permits of the support being adjusted to tubs of varying widths.
- 15 The supporting members 8 are also provided with contact members 31 similar in all respects to the contact members 27 provided with rubber or other suitable contact pads 32 similar to the pads 28. The said members 31 may be joined to their respective supporting members 8 by means of ball and socket joints similar to those shown in Fig. 3 in connection with the members 27.

The manner of using the present invention will be clear from the foregoing, but may be briefly stated as follows:

When it is desired to use the smaller infant's tub such as 5, the supporting device is placed within the standard tub such as 1 and the parts are so adjusted by means of the adjusting screws 21 as to cause the rubber pads 28 and 32 to contact with the sides 2 and 3 of the tub 1, as will be readily apparent. This adjustment is preferably accomplished with the hinges such as 11 slightly broken or open, so that when the smaller tub 5 is placed within the supporting members 15 and 16 the weight thereof will tend to close the said hinges and acting as a toggle, will force the rubber pads 28 and 32 into intimate contact with the sides of the tub 1. The device is preferably placed within the tub 1 in close proximity to the water faucets and outlet drain, and, as will be readily apparent, it may be adjusted at any height suitable to the person performing the bathing operation.

When the operation has been completed, the smaller tub may be removed from the supporting members 15 and 16 and the entire supporting apparatus readily removed from the tub 1 by merely breaking the hinges, which will permit of the supports being folded up, so that they occupy a very small space. The friction between the hinge members 10 and 11 may be readily controlled by means of the wing nuts 13 so that the parts will remain in any position in which they are placed.

It is obvious that those skilled in the art may vary the details of construction as well as the arrangement of parts without departing from the spirit of the invention and therefore I do not wish to be limited to the above disclosure except as may be required by the claims.

What I claim is:

1. In a device of the class described the combination of a plurality of transverse supporting members adapted to engage the sides of a bath tub; a plurality of longitudinal members extending between said transverse members and adapted to support a smaller tub; and connections rigidly securing said longitudinal members to said transverse members, and pivotally connecting said transverse members together in pairs, substantially as described.

2. In a device of the class described the combination of a plurality of pairs of transverse supporting members, each pair being pivotally connected together; means carried by each of said members adapted to frictionally engage the sides of a bath tub; and a longitudinal member, adapted to support a smaller tub, rigidly secured to adjacent members of each transverse pair, substantially as described.

3. In a device of the class described the combination of a plurality of pairs of transverse supporting members, each pair being pivotally connected together; cushioned means loosely carried by each of said members adapted to frictionally engage the sides of a bath tub; means for adjusting the length of said pairs of transverse members to accommodate different size tubs; and a longitudinal member, adapted to support a smaller tub, rigidly secured to adjacent members of each transverse pair, substantially as described.

4. In a device of the class described the combination of a plurality of pairs of transverse supporting members, each pair being pivotally connected together; cushioned means loosely carried by each of said members adapted to frictionally engage the sides of a bath tub; means for adjusting the length of said pairs of transverse members to accommodate different size tubs comprising a screw threaded member engaging one member of each of said pairs; and a longitudinal member, adapted to support a smaller tub, rigidly secured to adjacent members of each transverse pair, substantially as described.

In testimony whereof I affix my signature.

SELMA W. JEFFS.
